UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

HOLE-CLEANSING DEVICE.

Application filed March 24, 1924. Serial No. 701,369.

This invention relates to hole cleansing devices for rock drills. It has for its object to provide improved hole cleansing means. A further object is to provide improved means for conducting hole cleansing fluid to a hollow drill steel. A still further object is to provide improved hole cleansing fluid conducting means which has a conducting tube adapted to project within a hollow portion of a steel. A further object of the invention is to provide improved means whereby the cleansing fluid conducting tube which projects into the steel will automatically yield if the same should strike the end of the steel rather than be guided in to the hollow portion thereof upon insertion of the drill steel into the chuck mechanism of the drilling device, a further object being to provide improved means whereby when such a condition exists as just stated, the cleansing fluid through said tube will be automatically shut off and the operator thereby warned. It is also an object of my invention to provide such a mechanism so that the front part of the drilling motor will not be flooded with cleansing fluid when the conducting tube therefor does not assume its proper operative position. In the accompanying drawings I have shown for purposes of illustration one form which my invention may assume in practice. In these drawings.— Fig. 1 is a longitudinal vertical section through a rock drilling mechanism employing my improved hole cleansing means. Fig. 2 is an enlarged longitudinal vertical section of the means for controlling conducting fluid to the cleansing fluid conducting tubes. I have shown my improved device for purposes of illustration in connection with a usual drilling mechanism herein shown as of the stoper type and which comprises a usual percussive motor cylinder 1 having at its rear end a head 2 adapted to support in axial alinement with the cylinder 1 a feed cylinder 3 within which a usual feed piston 4 is reciprocably mounted and actuated by pressure fluid which is controlled by any suitable valve mechanism 5. A reciprocable hammer piston 6 within the cylinder 1 has a usual striking bar 7 projecting forwardly through a front head 8 and cooperating with a rifle nut 9 as by straight flutes 10 formed in the periphery of the striking bar 7, the rifle nut 9 being carried by a chuck bushing 11 rotatably mounted within a chuck housing 12 fixed upon the forward portion of the head 8 and all of these members being held in fixed relation by any suitable means such as side rods or other means (not shown). The type of drilling mechanism herein shown is also of the tappet type having a tappet 13 upon which the bar 7 strikes to actuate the hollow steel 14, said steel being held in the member 11 by any suitable construction 15. In order to supply cleansing fluid to the hollow portion of the steel 14, I have shown a usual inner liquid cleansing tube 16 supported by and projecting forwardly from the rear head 2 and terminating within the rear hollow portion of the steel 14. Mounted concentrically with the liquid cleansing tube 16 is a gaseous cleansing fluid tube 17 also supported by and projecting forwardly from the rear head 2 but terminating within the tappet 13 somewhat short of its forward end. More specifically, the tubes 16 and 17 are mounted within the rear head 2 as by the construction shown in Fig. 2. In order to accomplish the object of providing an automatic cut-off for the fluid flowing through the inner tube 16 in case the same should hit the end of the drill steel upon insertion of the same within the drilling mechanism, and also to allow the same to be yieldable upon the happening of such a condition, I have provided the following structure. Herein it will be noted that a threaded bore 18 is formed in a rear portion of the head 2 and terminates in an annular chamber 19 which has communication with a gaseous fluid supply passage 20. Projecting forwardly from the chamber 19 is a reduced bore 21 adapted to receive the tube 17 and made to have an air tight fit by providing a suitable leather packing 22 or other suitable structure which surrounds the tube 17 and against which is pressed a bushing 23 fixed upon the rear end of the tube 17 which, as shown in the figure, is flared outwardly at its outer end. In this construction, this bushing 23 is welded to the tube and thereafter ports 24 are drilled therethrough to allow communication with the chamber 19. The tube 17 is also held in fixed position by a bushing 25, having threaded engagement with the bore 18, which presses upon the rear portion of bushing 23. It will thus be seen 110

that air passing through the passage 20 may flow through the tube 17 independently of the inner liquid conducting tube 16.

In order to slidably and yieldably support the inner tube 16 a bore 26 is formed in the bushing 25 which has a closed end 27, there being mounted within this bore 26 a bushing 28 made of bronze, brass or other suitable non-corrosive material. The tube 16 projects rearwardly into bore 26 through a rubber packing 29 seated against the rear portion of the bushing 23, and also adapted to support the outwardly turned flange 30 of the tube 16. The flange 30 has abutting engagement with the forward portion of a cylindrical sleeve 31 slidably mounted within the bushing 28 and yieldably held in position as by a spring 32 which yieldingly holds the water tube 17 in its forward position.

In order to supply liquid or other cleansing fluid to the tube 16 I have provided a passage 33 controlled by any suitable means and terminating in an annular groove 34 formed in the rear portion of the head 2 which mates with a corresponding groove 35 formed in the forward portion of a cap 36 which has screw threaded engagement with the outer portion of the bushing 25. Communicating with the recess 35 is a port 37 terminating in a chamber 38 formed around the outer end of the bushing 25. This chamber can be formed as shown by turning down the outer end of the bushing 25 or could if desired be formed by any other suitable means. Leading from the chamber 38 are a plurality of forwardly projecting passages 39 terminating within the bore of the bushing 28 and which allows flow of fluid to the steel through openings 40 formed in the transverse portion of the front end of the sleeve 31.

In the operation of my device, fluid, either liquid or air, may be supplied to their respective tubes as desired by the use of any suitable valve controlling mechanism. Should the tube 16 by accident or otherwise engage the rear end of the steel instead of projecting into the hollow portion thereof, said tube will be thrust rearwardly against the tension of the spring 32 and sleeve 31 will overrun the ports 39 thereby cutting off liquid to the steel through the inner tube. The operator, upon seeing that no liquid is flowing to the steel, will thereby be warned that the tube does not have proper operative relation to the steel and that either a new steel is required or further adjustment of the existing one needed. Such a construction, it will be seen, serves several purposes; one of which is that it prevents damage to the inner tube for if said tube is held stationary it will be broken off upon engagement with the steel; while another is that the operator is warned that the inner tube does not have proper relation to the

steel and that the steel needs adjustment, while still another is that it also prevents the front end of the motor from being flooded with the cleansing fluid.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, a percussive drilling motor adapted to actuate a drill steel and having associated therewith steel supporting means adapted to support a hollow steel in position for actuation by said motor, and hole cleansing means comprising a cleansing fluid conducting element having its forward end normally in a position wherein it will lie within the bore of a hollow drill steel mounted in said supporting means in position for percussive actuation, supporting means for said element permitting the same to yield rearwardly but normally yieldingly maintaining it in its most advanced position, and cleansing fluid controlling means actuated upon yielding movement of said element.

2. In combination, a percussive drilling motor adapted to actuate a drill steel and having associated therewith steel supporting means adapted to support a hollow steel in position for actuation by said motor, and hole cleansing means comprising a cleansing fluid conducting element having its forward end normally in a position wherein it will lie within the bore of a hollow drill steel mounted in said supporting means in position for percussive actuation, supporting means for said element permitting the same to yield rearwardly but normally yieldingly maintaining it in its most advanced position, and cleansing fluid controlling means actuated by yielding movement of said element.

3. In combination, a percussive drilling motor adapted to actuate a drill steel and having associated therewith steel supporting means adapted to support a hollow steel in position for actuation by said motor, and hole cleansing means comprising a cleansing liquid supply element having its forward end normally in a position wherein it will lie within the bore of a hollow drill steel mounted in said supporting means in position for percussive actuation, supporting means for said element permitting the same to yield rearwardly but normally yieldingly maintaining it in its most advanced position, and cleansing fluid controlling means actuated upon yielding movement of said element.

4. In combination, a percussive drilling motor adapted to actuate a drill steel and having associated therewith steel supporting means adapted to support a hollow steel in position for actuation by said motor; and hole cleansing means comprising a cleansing fluid conducting element having its forward end normally in a position wherein it will lie within the bore of a hollow drill steel mounted in said supporting means in position for percussive actuation, supporting means for said element permitting the same to yield rearwardly but normally yieldingly maintaining it in its most advanced position, and cleansing fluid controlling means carried by said element and actuated by movement thereof.
5. The combination with a drilling mechanism having a motor and a hollow drill steel actuated thereby, of hole cleansing means cooperating with said steel comprising a plurality of cleansing fluid conducting elements, one of which is movable relative to the other and which is adapted to project into the hollow of the drill steel, means for yieldingly maintaining said movable element normally in its most advanced position relative to said other fluid conducting element, and fluid controlling means actuated on relative movement between said elements.
6. The combination with a drilling mech-
- anism having a cylinder and a hammer piston therein, a hollow steel, a yieldable cleansing fluid conducting tube extending through said piston and into said hollow portion of said steel at one end thereof, a bushing having a bore and fluid supply passages therein, said tube at its other end terminating in said bore, and a sleeve adapted to shut off flow through said passages and actuated by movement of said tube.
7. The combination with a drilling mechanism adapted to operate upon a drill steel and including a hammer element and a striking block for transmitting blows to a steel, of hole cleansing mechanism including a fluid conducting tube extending through the striking block and into position to enter a hollow steel and yieldable rearwardly on engagement by a steel, fluid supply means for said tube, and means for controlling said fluid supply actuated upon predetermined relative movement between said tube and striking block.
8. The combination with a drilling mechanism having a steel, of hole cleansing mechanism including inner and outer relatively movable fluid conducting tubes, fluid supply means therefor, and means for controlling said fluid supply actuated upon relative movement between said tubes.

In testimony whereof I affix my signature.
ELMER G. GARTIN.
